UNITED STATES PATENT OFFICE.

AUGUSTUS E. SMITH, OF LOS BANOS, CALIFORNIA.

MUSIC-LEAF TURNER.

SPECIFICATION forming part of Letters Patent No. 617,364, dated January 10, 1899.

Application filed October 28, 1897. Serial No. 656,701. (No model.)

To all whom it may concern:

Be it known that I, AUGUSTUS E. SMITH, a citizen of the United States, residing at Los Banos, in the county of Merced and State of California, have invented certain new and useful Improvements in Music-Leaf Turners, of which the following is a specification.

My invention relates to improvements in attachments to the desks or music-racks of pianos and similar musical instruments for holding and turning the leaves of the music book or sheet by the simple movement of a key; and the said improvements have for their object to produce a simple and effectively-15 working device that can be readily applied for operation to any piano or to a music-stand.

The said improvements comprise certain novel construction and combination of parts, 20 as hereinafter fully described, and pointed out in the claims at the end of this specification, reference being had to the accompanying drawings, forming a part thereof.

In the said drawings, Figure 1 is a perspective view of a device embodying my said improvements. Fig. 2 is a side elevation of the device. Fig. 3 is a detail side view of the spring-clip on the music-desk. Fig. 4 is a plan or top view of the leaf-turning mechanism, showing 30 a portion of the casing broken away. Fig. 5 is a longitudinal section through Fig. 4 on the line xx . Figs. 6 to 8, inclusive, are detail views, on an enlarged scale, of the cam and some of the mechanism within the casing and the parts 35 on the outside that connect the leaf-turning arms with the mechanism. Fig. 6 is a longitudinal section through the center of the cam. Fig. 6^a is a top view of the cam. Fig. 7 is a longitudinal section through the central rod 40 or spindle and the sleeve which operates the first leaf-turning arm. In this figure one of the leaf-turning arms is represented as raised from its position on the rod to show more clearly the latch T and the groove V. Fig. 45 7^a is a cross-section at xy , Fig. 7. Fig. 7^b is a view in cross-section through yy , Fig. 7. Fig. 8 is a top view of the sleeve or hub that actuates the second one of the leaf-turning arms. Fig. 9 is a detail view, on an enlarged 50 scale, of a portion of the turning-post that actuates the music-turning arms. Fig. 10 shows

in detail the front and side views of the spring-latch that locks the arms to the post. Fig. 11 is a cross-section through the post at yz , Fig. 10. Fig. 12 is a side view of the spring-clip 55 on the end of the leaf-turning arm, and Fig. 13 is an end view of the same. Fig. 14 is a longitudinal section taken through the case at the line zz , Fig. 4.

A indicates a box or case inclosing the operating-cam and other parts of the mechanism.

B is a bar or strip having a pitch or inclination backward to support the music at a suitable angle.

B' B' are boards or leaves attached by hinges to the center bar to fold together for convenience in shipping the attachment or in putting it away when not required for use. When folded out flatly, these boards and the center 70 bar B form the desk or support for the music.

C are narrow boards attached to the case A by hinges c^x c^x on each side to fold up against the case after the boards B are closed. In their extended position these boards C C 75 lie horizontally and form a stable base for the attachment.

D is a spring-clip on the fixed center bar, adjustable up and down to accommodate sheet-music of different sizes and constructed, as shown in Fig. 3, with a stationary jaw d^x , a hinged jaw d^l , and a sleeve d^2 , fitted to slide on a guide-rod d^3 . The sleeve is set in about flush with the front of the center bar, and the rod d^3 is fixed in the groove. The 80 jaw d^x is rigidly secured to the sleeve, and the movable jaw d^l , pivoted to the sleeve d^2 , is provided with a thumb-piece d^5 on the upper end, under which is placed a spring d^4 to hold the jaws closed with proper degree of pressure. A lip or projection d^7 on the hinged jaw, which bears against the rod, serves to lock the sleeve and prevent it from slipping on the rod. When the thumb-piece d^5 is depressed, this lip is drawn away from the rod 95 and the sleeve is movable up or down. The lower edge of the music-sheet rests on the top of the case A between the center bar B and the spindle on which the leaf-turning arms are mounted.

The leaf-turning arms are formed of rods E E', each secured to a separate sleeve and

carrying on the outer end a spring-clip F, the construction of which is shown in Figs. 12 and 13.

5 F are two jaws with knuckles f^x f^x fitted loosely on the arm to open and close like a pair of nippers, and f^2 is a coil-spring placed between the lower members of the jaws to press the upper edges together. The lower ends of the jaws form finger-pieces for opening the gripping ends.

10 The cam G is formed with a groove g of proper shape to produce one-half of an entire revolution of the cam by the vibratory movement of a lever H, having a fulcrum h' and 15 extending through a slot a^x in the front of the case to the outside. A pin h^3 on the inner end of this lever lies in the groove of the cam, so that by depressing the key on the outer end of the lever the short perpendicular movement of the inner ends turns the cam G on its center about a half of a complete revolution. A coil-spring h^3 on the fulcrum-post h' of the key raises the key and throws back the cam to its starting-point.

20 25 The cam being fixed on the spindle or post K, the latter is rotated in the bearing a^3 at the bottom and a^4 in the top of the case, first in a forward direction, or from right to left, by the depression of the key, and afterward 30 in the contrary direction, or back to the starting-point, by the reaction of the coil-spring h^3 . At the beginning of every movement in the forward direction a leaf-turning arm is 35 locked to the post K and is carried over to the left side of the desk; but on the return movement of the cam and the post K the arm previously carried over is released from the post and held by a locking-dog L, so that the cam and the post return without the arm.

40 45 The locking-dog is attached to a lever L' and works through a slot L^3 in the top of the case. The lever L' is fulcrumed at L^4 and extends through a slot a^6 in the front of the case. A leaf-spring L^5 throws up the lever when the pressure of the finger is taken off. As each 50 leaf-turning arm in succession rides over the dog L it is held and kept in position at the left-hand side of the desk until the lever L is depressed, at which time a single movement of the lever releases all the arms.

55 60 The first or lowest one, E, in the set of leaf-turning arms is locked to the cam by a tooth m in a recess in the top of the cam and a lug p on the lower end of the sleeve E², to which the arm is fixed, so that the sleeve is locked to the cam at the initial movement of the last-named piece and is carried with it; but on the return or contrary rotation the cam leaves the sleeve in such position with the arm E at the left-hand side of the case. The return throw of this arm when released from the dog L is effected by a coil-spring P, one end of which is secured to a fixed point in the case and the other end to the sleeve E². The next 65 leaf-turning arm E' is locked to the post at the next rotative movement of the cam by a spring-latch working in a groove in the post

and engaging a slot in the sleeve of the arm, the construction of which is as follows: A groove S is cut in the post K and a flat spring 70 T, having two projecting teeth or nibs t' t^2 , is set in the groove and secured at the lower end, leaving the upper end portion free to spring out and throw the nibs beyond the face of the post. In line with the lower nib t' is cut a groove v in the inner face of the sleeve E² for about one-half the circumference of the bore of the sleeve x , and in the bottom of the other sleeve E³ is cut a slot or recess v' , that comes in line with the top nib t^2 and is caused to engage that slot when the spring-latch is thrown out of the groove in the post. These grooves in the two sleeves and the projecting nibs of the spring-latch are so arranged that when the arm E is left 80 at rest at the left side of the desk and the cam brings the post back again to the starting-point the lowermost nib t' will spring into the groove v , and thus allow the upper tooth or nib t^2 to spring out of the slot in the post 85 and engage the slot v' in the bottom of the sleeve E³. This locks that sleeve to the post, and as the key D is depressed the cam will 90 turn the post and carry around to the left the second leaf-turning arm. By the movement 95 of the first arm E from right to left the coil-spring P is wound up and remains in tension as long as the arm is held in position by the locking-dog L; but on depressing the lever L' the arm is released, allowing the spring to 100 react, and thereby carry all the arms on that side over to the right-hand side. This movement allows a page of the music to be turned back again for repeating passages when desired.

105 In the above construction two leaf-turning arms are described and shown, but several additional arms can be added and the number increased by providing on the same post, which will be increased in length for that purpose, an additional spring-latch with two ribs t' t^2 and a corresponding arrangement of grooves in the sleeves of the additional arms. Thus for a third arm the sleeve E³ of the second arm has a groove v^3 , which corresponds 110 in length with the groove v in the sleeve E², and a spring-latch T is set in a groove in the post in required position to bring its nibs into line with the groove v^3 in the sleeve E³ and with the groove or slot provided in the sleeve 115 of the third arm to engage the top nib of the latch. This locking mechanism is identical in its construction and operation with that which locks the second arm to the post, and thus any required number of leaf-turning 120 arms can be provided in this mechanism simply by increasing the length of the post and providing additional spring-latches.

125 As thus constructed and arranged for operation, the device is actuated by a depression of the right-hand key, a single movement of which will throw an arm and carry the leaf confined in the clip on the end of the arm over to the left-hand side of the desk and

leave it there, or by depressing the key at the left the arm will be thrown back to its first position, carrying the leaf of music back again.

Having thus fully described my invention, 5 what I claim as new, and desire to secure by Letters Patent, is—

1. The combination of the center bar hinged boards guide-rod on the center bar, stationary rod, sliding sleeve, spring-jaws secured 10 to and carried by said sleeve one of said jaws being stationary and the other adapted to open and close, and the lip or projection on the hinged jaws arranged to bite the stationary rod and hold the sleeve, a case at the bottom of the center bar, a rotatable post having 15 bearings in said case, a cam giving motion to said post, a lever engaging the same cam and rotating the same by depressing the outer end thereof, leaf-turning arms mounted for rotation on said post, mechanism locking said arms to the post in successive order at each 20 rotative movement of the post from right to left and releasing said arms by a reverse movement and a coil-spring adapted to be wound up by the forward throw of the first 25 leaf-turning arm and by reaction to throw the arms back again from left to right, and a locking device and an operating-lever arranged to hold the arms when thrown over to the left.

2. In a device for turning leaves of music, 30 the combination with a suitable desk; of the rotatable post, grooved cam fixed on said post and having a recessed end and a tooth in said recess, a cam-actuating lever, a leaf-turning

arm having a clip on the outer end, a sleeve 35 on the inner end fitted loosely upon the post, a lug on the lower end of the sleeve, a concentric groove in the base of said sleeve, a sleeve superposed on the sleeve of the lowermost arm and carrying a second arm, a spring-latch in 40 the post having nibs or projections and grooves in the said sleeve arranged with relation to the nibs of the spring-latch for operation as set forth.

3. In a music-leaf turner, the combination 45 of the center bar, hinged and folding boards on the sides, case at the bottom of the center bar having hinged base-boards, a rotatable center post in said case, leaf-turning arms centered on said post, means for locking said 50 arms to the post under its rotative movement in one direction, a locking device to hold said arms at rest when thrown over to the left side of the desk, a pivoted lever projecting from the front of said case and means connecting said lever with the post and adapted by the downward movement of the lever to produce rotary movement of the post, and a spring for returning said arms to their original position when released from the locking 55 means.

In testimony that I claim the foregoing I have hereunto set my hand and seal.

AUGUSTUS E. SMITH. [L. S.]
